ART OF ELECTRICAL PRECIPITATION

Richard Heinrich, Berlin-Sudende, and Wilhelm Feldmann, Berlin-Spandau, Germany, assignors to International Precipitation Company, Los Angeles, Calif., a corporation of California

Application December 3, 1931, Serial No. 578,830
In Germany December 16, 1930

1 Claim. (Cl. 183—7)

This invention relates to an improved method and apparatus for electrical precipitation, and the main object of the invention is to provide for energizing electrical precipitating apparatus in such manner as to increase the efficiency of the precipitating operation and increase the working capacity of the apparatus.

In the usual operation of electrical precipitators, an electrical field is maintained between electrodes adapted to produce electrical discharge into the gases in such manner as to cause precipitation of suspended particles and collection of same on the electrodes. The high potential difference between the electrodes necessary to produce the required electrical field has been usually produced by supplying to the electrodes a unidirectional current of suitable high tension, such current being obtained by rectifying an alternating current of ordinary commercial frequency. In order to operate the electrical precipitator effectively, the high potential difference applied to the electrodes in this manner must be sufficient to produce silent electrical discharge into the gases being treated, and the discharging effect and resulting precipitating action increase as the potential difference is raised, so that in order to obtain maximum efficiency and working capacity of the precipitator, it is desirable to maintain the potential difference as high as possible. The potential difference that can be maintained between the electrodes is, however, limited by the tendency to disruptive discharge between the electrodes, which has to be avoided as far as possible. The operating potential difference that can be maintained in the precipitator is therefore limited to the range between the potential difference necessary to produce ionization and the potential difference resulting in excessive disruptive discharge.

It has been found that the efficiency and working capacity of electrical precipitating apparatus can be increased by applying to such apparatus intermittent impulses of such high peak voltage as to result in momentary increased ionization in the precipitator, the period during which this high voltage is maintained during each such impulse being, however, of such short duration as to prevent or minimize disruptive discharge between the electrodes. In this manner a sudden electrical potential difference may be applied to the electrodes whose peak voltage is far in excess of that which can be applied as a steady potential difference without resulting in excessive disruptive discharge or breakdown of the dielectric between the electrodes.

In applying such a momentary high potential impulse or shock voltage impulse to an electrical precipitator of large operating capacity, such as is necessary for treatment of large volumes of gas, it is found that on account of the large electrostatic capacity of such an apparatus it is difficult to obtain the required sudden or abrupt increase in potential difference or steep wave front between the electrodes and the short period of high potential which is requisite for the effective functioning of the voltage impulses, on account of the tendency of such impulses to be flattened out by the effect of the large electrical capacity of the precipitating apparatus. An important object of the present invention is to enable such shock potential or voltage impulses to be efficiently applied to an electrical precipitator of large size and to enable the desired momentary high potential difference to be produced between the electrodes of the precipitator irrespective of the size of the precipitator.

According to the present invention, the electrical precipitating apparatus is subdivided into a plurality of sections and the voltage impulses are applied successively to the several sections, each of such sections being of such small size and small electrostatic capacity that the voltage impulses are delivered with full effect to each section and the requisite high potential difference is momentarily applied thereto to produce the desired increased ionization.

The accompanying drawing illustrates embodiments of our invention and referring thereto:

Fig. 1 is a diagram of the circuit including the electrical precipitating apparatus and the energizing circuit therefor.

Fig. 2 is a diagram showing a modified form of rectifying means used in connection with the apparatus for generating the shock potential impulses.

Fig. 3 is a graph showing the relation between voltage and time, in an electrical precipitator operated in accordance with this invention.

Referring to Fig. 1, the electrical precipitator is shown diagrammatically as comprising a plurality of sections 1, each section comprising one or more discharge electrodes 2, and corresponding opposing or collecting electrodes 3, which are mounted in any usual manner and insulated from one another as well known in the art. The discharge electrodes may be formed as wires, rods, chains or screens, of relatively small area, adapted to facilitate electrical discharge therefrom, and the opposing electrodes may be formed as tubes, plates or screens of relatively large

area, adapted to minimize electrical discharge. The opposing or collecting electrodes 3, may be grounded as indicated at 4, and the discharge electrode means 2 are connected by conductors 5, 2' to current distributing means 5, whereby said conductors 2' are successively connected to an energizing circuit connection 6, leading from the means for generating shock potential or voltage impulses.

- 10 The distributing means 5 may comprise a rotating arm 5a making contact with fixed contacts 5b connected to the respective lines 2' leading to the precipitator sections, said arm 5a being rotated at suitable velocity by a motor 7 which may be an electric motor provided with suitable speed reducing means.

The means for generating shock potential or voltage impulses may comprise a step-up transformer whose primary winding 8 is connected to 20 any suitable alternating current service circuit and whose secondary winding 9 is connected through rectifying means and spark gap means to the connection 6 aforesaid. In the form shown in Fig. 1, the rectifying means comprises two 25 thermionic valve tubes 10 and 11, whose filament terminals are connected to opposite ends of the secondary winding 9 (said winding having a central ground connection 13) and whose plate terminals are connected to wire or conductor 12 for delivering rectified current impulses of high 30 potential difference, said wire 12 being in connection, as hereinafter described, with the wire 6 leading to the electrical precipitator sections. Suitable transformers indicated at 14 and 15 are 35 provided for energizing the filaments of the respective thermionic valve tubes.

A spark gap means 17 is connected between the rectifying means and the wire 6, so that the electrical potential difference generated by the step-up 40 transformer and rectified by the rectifying means, is by the operation of such spark gap applied intermittently to the connection leading to the precipitating apparatus in the manner hereinafter described. We also prefer to provide suitable capacity means in the connections 45 of the spark gap so as to store electrical energy in such manner as to increase the suddenness and magnitude of the shock potential difference or voltage impulse applied to the precipitating apparatus. The capacity effect may be obtained 50 by means of a condenser 19 connected between the line 12 and ground 19' or, if desired, the line 12 may be formed in part as a cable having an outer metal casing 21, grounded as indicated at 55 21', a suitable solid dielectric 22 being provided between said casing and the line 12, the electrostatic capacity of such cable being such as to provide the required electrostatic capacity for supply of sufficient energy to the spark gap. If 60 desired, both the cable and the condenser may be used to provide the desired capacity.

The spark gap means 17 is preferably provided with cooling means, such as means for applying a stream of cooling gas thereto, in order 65 to prevent undesirable residual conductivity of the spark gap when the energizing impulse ceases.

In case a separate condenser is used, such as indicated at 19, it is placed between the generating means and the spark gap, preferably in the 70 immediate neighborhood of the latter, so that disturbing action due to the self-induction of the line is avoided.

In many cases it is advantageous to interpose 75 in the line a non-inductive resistance, indicated at 23, of such magnitude as to prevent the propa-

gation of oscillations back through the line. Also, a self-induction coil, such as indicated at 24, may be provided in advance of the connection of the condenser 19 so as to suppress high frequency oscillations in the line between the generating means and the spark gap.

The operation is as follows: Alternating current is supplied to the primary winding 8 of the transformer and the alternating high tension current thereby generated in the secondary winding, is rectified by the action of the valve tubes 10 and 11 in well known manner, so as to produce rectified high tension current waves corresponding to both half waves of the alternating current. The electrical energy thus supplied to line 12 is stored in 10 the capacity means ahead of the spark gap 17, such capacity means being provided either by condenser 19 or by means of a cable having the necessary capacity, as above described. Such capacity means eventually becomes charged to sufficiently high voltage to cause a spark to pass through the spark gap 17, the electrical resistance of said gap being thereby momentarily greatly decreased with the result that a high potential impulse or voltage impulse having a steep wave 15 front is momentarily imparted to the line 6 leading to the precipitating apparatus. By the operation of the distributing switch 5, this impulse is communicated to the line 2' leading to the particular electrical precipitator section which is at 20 that moment in connection with the contact arm 5a of said switch, and in the operation of said switch, this connection is progressively shifted so as to bring the respective precipitator sections 25 successively into connection with the charging line 6 and apply the voltage impulse or impulses 30 to each precipitator section in succession. It will be observed that the electric current is rectified before reaching the condenser, so that the high potential impulses produced by discharge of said 35 condenser across the spark gap are unidirectional impulses, that is, all of said impulses are in the same direction. Consequently, these impulses serve to create a unidirectional field in the respective precipitator sections.

The connections of the spark gap circuit are preferably such that only enough energy is thus supplied to the precipitating field of each section that the voltage therein exceeds the ionization voltage for only a short time at each voltage impulse and then falls again to approximately the voltage at which ionization ceases. The development of disruptive discharge in the precipitator is thereby effectively suppressed. By the method and apparatus above described it is possible to 40 apply to the electrical precipitator sections a momentary voltage as much as 80% in excess of that 45 which can be applied by means of the usual rectified alternating current.

By appropriate selection of the voltage, electrostatic capacity, and resistance of the precipitator line, the rapidity at which the voltage impulses succeed one another can be regulated within wide range so that the conditions best adapted for the operation of the precipitator can be obtained, for example, by increasing or decreasing the electrostatic capacity the rapidity of sequence of the sparks can be varied between from several hundred impulses per second down to say one impulse per second. Each voltage impulse 70 is initiated when the condenser 19 or other capacity means becomes charged by the generating means to the sparking potential for the gap, and the energy which has been stored in the line due to its electrostatic capacity is then dis- 75

charged through the spark gap to the particular precipitator section which for the time being is in connection therewith, the time required for discharge of such energy depending upon the capacity in connection with the spark gap, and the time required for charging the condenser before another spark occurs also depending on such capacity, so that by proper adjustment of the electrostatic capacity, as stated, any desired 10 rapidity of sequence of voltage impulses may be provided.

It will be understood that the time between successive breakdowns of the spark gap, and consequently the number of impulses impressed upon 15 the precipitator in a given unit of time, depends entirely upon the characteristics of the circuit and not upon the frequency of the rectified alternate current impulses used for charging the condenser 19.

20 In Fig. 3, time is plotted horizontally and voltage vertically. The voltage supplied to the electrical precipitation apparatus by the above described impulse circuit is indicated by the line A—A, while the line O—O represents zero voltage. Successive impulses are shown as starting at the times indicated at t_1 , t_2 and t_3 , while the period between successive impulses is indicated at T. At the time of each such impulse the voltage rises rapidly from V_1 to V_2 . The latter 30 value represents the maximum or peak voltage attained at the precipitator during each impulse. The voltage across gap 17 falls almost instantaneously to a sufficiently low value to break the spark, and the energy stored in the circuit is rapidly dissipated, causing the voltage between the precipitator electrodes to fall rapidly to approximately the value at which ionization in the precipitator ceases to occur, after which the voltage falls more gradually to the value V_1 , before the start of the next succeeding impulse. 35 It will be understood that the voltage plotted in Fig. 3 represents the voltage applied to the electrical precipitating apparatus as a whole, and that one or any desired number of successive im-

pulses of the character shown may be applied, in turn, to the respective sections 4, depending upon the relation between the rapidity of sequence of the impulses and the speed of operation of the distributing switch 5.

By the above described means, it is possible to apply the high voltage impulses to a large precipitating apparatus as efficiently as to a relatively small precipitating apparatus.

The distributing switch 5 may be operated at 10 such rate as to put each precipitator section in connection with the spark gap for a sufficient time to receive one or any desired number of impulses therefrom.

Any other suitable means may be provided for 15 generating the required unidirectional high potential difference for energization of the spark gap. For example, as shown in Fig. 2, instead of the thermionic valve tubes shown in Fig. 1, we may use a mechanical rectifier such as indicated at 25 having terminals connected to the secondary winding 9' of the step-up transformer having a ground connection indicated at 13' and a line connection indicated at 12', the latter leading to the spark gap means in the same 20 manner as above described.

This application is a continuation in part of 25 our application Serial No. 527,690, filed April 4, 1931.

We claim:

The method of electrical precipitation which consists in storing electric energy in a condenser in connection with a spark gap until the spark potential of said gap is reached, thereby delivering 30 a high voltage impulse through said spark gap, repeating said operations so as to produce a succession of such impulses, and applying such high voltage impulses to energize successively, one at a time, a plurality of electrical fields containing gases carrying suspended material so as 35 to effect electrical precipitation by the action of said electrical fields.
